[57] CLAIM

The ornamental design for electronic meter for determining human pulse rate from a fingertip, as shown.

DESCRIPTION

FIG. 1 is a perspective view of an electronic pulse meter for determining human pulse rate from a fingertip, showing my new design;

FIG. 2 is a top plan view of the pulse meter of FIG. 1.

FIG. 3 is a side elevation of the pulse meter as it is shown in FIG. 2.

FIG. 4 is a bottom plan view of the pulse meter of FIG. 1.

FIG. 5 is a right end elevation of the pulse meter as shown in FIG. 2.

FIG. 6 is a left end elevation of the pulse meter as shown in FIG. 2.
